UNITED STATES PATENT OFFICE.

JOSEPH R. MERRIHEW, OF LYNN, MASSACHUSETTS.

COFFEE-SEPARATOR.

SPECIFICATION forming part of Letters Patent No. 277,817, dated May 8, 1883.

Application filed November 29, 1882. (No model.)

To all whom it may concern:

Be it known that I, JOSEPH R. MERRIHEW, of Lynn, in the county of Essex and State of Massachusetts, have invented certain Improvements in Coffee-Separators, of which the following is a specification.

This invention relates to that class of coffee-separators in which an inclined belt or endless apron is employed, which is so driven by supporting-pulleys that its upper inclined surface will move upwardly, so that when coffee-berries are dropped upon the belt the round berries will roll by gravitation to the lower end of the belt, while the partially-flat berries will 10 lodge on the belt and be carried upwardly thereby and discharged from the upper end, the two kinds of berries being thus separated.

My invention has for its object to provide certain improvements in a machine of this 20 class, whereby the berries may be evenly fed from the hopper to the inclined belt.

To this end my invention consists in the improvements which I will now proceed to describe and claim.

25 Of the accompanying drawings, forming a part of this specification, Figure 1 represents a side elevation of a coffee-separator embodying my invention. Fig. 2 represents a top view of the same. Fig. 3 represents an enlarged transverse section of the lower portion 30 of the hopper and its feeding devices, and Fig. 4 represents a perspective view of one of the devices for preventing the partially-flat berries from rolling downwardly.

35 The same letters of reference indicate the same parts in all the figures.

In the drawings, A represents an inclined supporting-frame, in the opposite ends of which are journaled two horizontal rolls, B B', one 40 being considerably higher than the other.

C represents a belt or endless apron, of canvas or other suitable material, supported in an inclined position by the rolls B B', and driven so that its upper surface will move upwardly 45 by power applied to the roll B.

C' represents a hopper supported over the belt C by the frame A. In the lower portion of the hopper is journaled a feed-roll, D, which is belted to a pulley on the driving-roll B, and 50 is rotated thereby in the direction indicated by the arrow in Fig. 3. Over the feed-roll D is

located a horizontal toothed plate or comb, E, having teeth e, separated by slots or spaces of sufficient width to permit coffee-berries to pass easily between said teeth. The comb E is attached to a horizontal slide or bar, I, that is adapted to be moved transversely of the machine, and is moved first in one direction and then in the opposite direction by two cams, G G', projecting from opposite sides of a disk, G², attached to the arbor of the roll D, said cams acting alternately on lugs or fingers H H, projecting from the bar I. The reciprocating movements of the comb E create a constant agitation of the coffee-berries in the hopper, 65 and cause them to descend evenly and with the desired rapidity upon the roll D, and prevent them from becoming clogged over the roll and failing to be ejected thereby from the hopper, as they might do without the reciprocating comb, the feed-roll D being smooth-surfaced. It will be seen that the smooth-surfaced feed-roll insures the even passage of the berries from the hopper, so that they fall continuously upon the belt, and not intermittently, 70 as would be the case if the feed-roll had cells or pockets in its periphery. The reciprocating comb and rotary roll constitute an efficient and noiseless feeding device, which is operated at much less expense of power and with much 75 less wear and jar than a hopper which is shaken or reciprocated to deliver the berries. When the berries drop upon the belt or apron, the round ones immediately roll downwardly and accumulate in a box, K, at the lower end of the 80 belt, and the greater part of the partially-flat ones lodge on the belt, and are carried upwardly thereby until they drop over the upper roll, B, into a box, L. It is found, however, that some of the partially-flat berries will commence to roll downwardly when they first strike 85 the belt or apron, and unless their momentum is checked they will find their way into the receptacle K with the round berries. To check the downward movement of such berries, I 90 provide one or more series of combs, M, arranged crosswise of the belt C, as shown in Fig. 2. Each series is composed of several sections, and each section is composed of a toothed plate pivoted upon a supporting-rod, N, so that 95 the outer ends of the teeth will bear with a yielding pressure on the belt C, said pressure 100

being due to the weight of the sections. The teeth t of each section are separated by spaces of sufficient width to permit the round berries to roll easily through. Each section is provided with two tubes, v , on its upper surface for the reception of the rod N .

I do not claim the comb-sections, however, as I am aware that similar devices have been before used for the same purpose.

10 I claim—

In a coffee-separator, the combination of the inclined belt or apron, the hopper over the same, the smooth-surfaced, positively-rotated roll D , located in the lower portion of the hop-

per, the comb or slotted plate located over the 15 roll D , and a connection between said comb and the arbor of the roll D , whereby the comb is caused to feed the coffee-berries regularly, uniformly, and noiselessly upon the roller and apron, as set forth.

20

In testimony whereof I have signed my name to this specification, in the presence of two subscribing witnesses, this 24th day of November, 1882.

JOSEPH R. MERRIHEW.
